UNITED STATES PATENT OFFICE.

CHARLES D. MATTISON, OF HASBROUCK HEIGHTS, NEW JERSEY, ASSIGNOR TO THE UNITRIM COMPANY, INC., OF NEW YORK, N. Y., A CORPORATION OF NEW YORK.

TRIMMING-MACHINE.

1,240,237.

Specification of Letters Patent. Patented Sept. 18, 1917.

Application filed December 31, 1913, Serial No. 809,621. Renewed February 26, 1917. Serial No. 151,145.

To all whom it may concern:

Be it known that I, CHARLES D. MATTISON, a citizen of the United States, and resident of Hasbrouck Heights, in the county of Bergen and State of New Jersey, have invented 5 certain new and useful Improvements in Trimming-Machines, of which the following is a specification.

This invention relates to a machine for 10 trimming fabrics having embroidery or other raised work thereon. Its principal object is to provide a machine of simple and efficient construction and operation whereby the trimming of the fabric along a path defined by the contour of the relief or raised 15 work shall be rapidly accomplished. To this end my invention, broadly considered, comprehends a trimming machine having a cutting element, the successive functional positions of which in respect to the cutting path 20 are determined by the relief of the fabric irrespective of the configuration or ornamentation of the relief.

The invention also comprises novel feed 25 mechanism whereby the fabric may be fed in a variable path.

The invention also comprises various features of construction and combinations of parts whereby the feeding of the fabric and 30 the progressive operations of the cutting element are relatively effected and controlled, all of which, together with structural characteristics whereby advantages are secured, will be hereinafter particularly described 35 and claimed.

While I have shown in the drawings and shall hereinafter describe in detail a machine illustrating a preferred form of embodiment of my invention, it is to be understood that I 40 do not limit myself to the precise mechanisms pointed out, as the same may be modified without departing from the spirit of the invention. It is further to be understood that while the form of machine herein 45 illustrated is particularly designed for the trimming of embroidered fabrics, yet the apparatus may be adapted to the trimming or severing of any kind of fabric having raised or relief work thereon of any form or configuration; such raised or relief work in any case being the determining factor for the path of the cutting element during the trimming or severing operation. Furthermore, that while the feed mechanism embodying 50 my invention is especially adapted to use in

connection with trimming instrumentalities of the character herein set forth, such feed mechanism is not limited to use in that specific relation.

In the accompanying drawings—

Figure 1 is a vertical section, partly in elevation, of a trimming machine embodying my invention.

Fig. 2 is a transverse horizontal section, as on the line 2—2 of Fig. 1.

Fig. 3 is a partial transverse section, enlarged, as on the line 3—3 of Fig. 5, showing the rack and pinion devices, and adjuncts, for rotating the cutter rod. In this view the rack is shown at the limit of its forward 70 stroke.

Fig. 4 is a similar section showing the position of the parts with the rack at the limit of its rearward stroke.

Fig. 5 is a transverse vertical section 75 through the machine, as on the line 5—5 of Fig. 1.

Fig. 6 is a transverse horizontal section as on the line 6—6 of Fig. 1.

Fig. 7 is a sectional detail as on the line 80 7—7 of Fig. 5.

Figs. 8, 9 and 10 are views, in plan, of the cutter and feed heads, showing the cutter in various angular positions.

11 is a suitable casing within which are 85 contained the various mechanisms, with the exception of the die plate 12 and its supporting and actuating parts. The top 13 of this casing constitutes a work table through a suitably disposed opening 14 in 90 which are operable the feed and cutting devices to be hereinafter described. The die plate is movable toward and from the feed so that it may be lowered upon or raised 95 from the interposed fabric to be trimmed. In the present instance the die plate comprises a disk having a central stud 15 which is adapted to be detachably fitted to and clamped by the lower bored and split end of a vertical stem 16. This stem is slidingly 100 mounted in the tubular end of an arm 17 rising from and overhanging the table, and is maintained normally in depressed or work engaging position by the action of a flat spring 18 upon the head of the stem, which spring is conveniently affixed to a suitably disposed projection 18^x on the arm. Extending from the stem through a vertical 105 guide slot 20 in the arm is a lateral stud 21 with which co-operates an appropriate cam 110

lever 22 which is pivotally supported on the arm. The cam surface of this lever is so shaped that by the act of lifting the lever the part 23 of such surface, impinging 5 against the stud, raises the stem and die plate, and the part 23^x then contacts with the stud and serves as a rest therefor to maintain the stem and die plate in raised position. A downward movement of the 10 lever will permit the stem and die plate to resume their down position. The cam lever is held normally in engagement with the stud 21 by the action of a spring-pressed stud 24 against an angular shouldered portion 25 of the lever, which latter stud projects through a horizontal slot 26 in the arm 17 and co-acts with the shouldered portion to lock the lever and the die plate devices in lowered position. The stud 24 extends 15 from a horizontally movable pin 27 which is fitted to a socket in the arm and is normally pressed toward the outer end of the latter by a spring 28 confined within the socket. Any other suitable means for operating the die plate may be employed.

The feed includes a cylindrical head 29 the upper serrated work-engaging edge of which is disposed directly beneath the die plate. This head has capacity for variable 30 movement vertically and horizontally as may be prescribed by the nature of the fabric and the contour of the embroidery or other relief thereon, as will presently appear. The head is slidably fitted for relative 35 vertical movement within the upper cylindrical extension 30 of a hollow cone 31 which depends below the table, the head being maintained yieldingly raised by the action of a spring 32 suitably disposed within 40 the head and the extension. The extent of relative vertical movement of the head is limited by a stud 33 thereon projecting into a vertical slot 34 in the extension 30.

In the present instance the extension is 45 slidably fitted to a collar 35 having a rounded bearing member 36 which is seated for rocking movement within a corresponding socket member 37 located within the opening 14 of the table. The socket member 50 37 depends from the upper and is secured to the lower of two spaced rings 38 which freely embrace the table, so as to permit a limited horizontal movement in all directions of such member and the parts supported thereby. The rings 38 close the opening about the feed and thus preclude the 55 entrance of lint and pieces of severed fabric to the interior of the casing and the mechanism therein. This cover structure may be 60 omitted if desired.

The basal portion of the hollow cone 31 is provided with laterally-extending lugs 39 to which are secured the upper ends of two depending rods 40, the lower ends of which 65 are connected by a yoke 41 which consti-

tutes one member of a universal-joint connection. The other member of this connection comprises a cruciform bar 42 one arm of which is pivoted at its ends to the sides of the yoke, as by screw points 43, and the 70 ends of the other arm are pivoted, as at 44, to and between the forked arm of a crank lever 45 which is fulcrumed to the side of the casing, as at 46. The other arm of this lever extends adjacent a race cam 47 which is formed on or affixed to a driving wheel 49 mounted to turn on a fixed stud within the casing, the lever arm being equipped with a roll 50 which runs in the cam groove. This cam groove being of oval form is 80 adapted during its rotation to effect the timely oscillation of the crank lever and the universal joint connection, thereby transmitting through the rods 40 an up and down motion to and yet permitting variable 85 horizontal movement of the hollow cone and its feed head. Encircling the cone is a vertically reciprocable ring 51 which, in conjunction with an internal eccentric member 52 within the latter, acts upon the external 90 and internal surfaces respectively of the cone to control and determine the variable movement of the cone and the feed head. The ring 51 is borne by the upper end of a vertically reciprocable frame including two 95 upright parallel bars 53, which are supported by and between guides 53^x on the inner side of one of the walls of the casing. A cross-piece 54 of the frame is connected by means of a link 55 with a lever 56 which is 100 pivotally supported at one end on a lug on the casing. The other end of this lever is connected by means of a link 57 with the end of a lever 58 that is, in turn, pivotally supported on a lug on the casing. The lever 105 58 lies laterally adjacent the cam 47 and is provided with a roll 59 that runs in the cam groove, whereby during the rotation of the cam the lever and link connections are 110 actuated to effect the timely rising and falling motion of the frame and its appurtenances.

The internal eccentric member 52 above referred to has an outer inclined edge which is adapted to contact with the internal wall of the hollow cone and thus in connection with the external ring control the positions of said cone and its adjuncts. This member 52 is formed on or affixed to the upper end of a sleeve 60 which is splined to a vertically extending cutter rod 61 having capacity for oscillatory as well as vertical movement within defined limits, as herein-after described, and hence the sleeve partakes of the rotary motion of the cutter rod. 115 In the present instance the sleeve is provided with a circumferential flange 62 which is seated between the cap and body sections respectively of a cylindrical bearing member 63 which is fitted to an orifice in an arm 120 125

64 extending forwardly from the frame. The member 63 is held in place by a set-screw 65 in the arm entering an annular groove in the said member. A part of the 5 periphery of the flange is cut away, as at 66, in a manner to contact with its stationary seat and perform the function of a brake to resist the rotation of the cutter-rod, as will be hereinafter described.

10 The lower end of the vertically-movable frame is provided with a forwardly-extending arm 67 having therein, in axial alignment with the cutter rod, a vertically-adjustable stop, comprising, in the present instance, a screw stud 68, having, preferably, a jam-nut 69 which takes against the underside of the arm. This screw-stud is adapted in the upward movement of the frame to take against the lower end of the vertically-disposed cutter rod, and force the cutter 20 thereof through the opposing fabric, as will presently appear. The rod extends through the hollow cone, and bears at its upper end a cutter-head the functional edge 25 of which extends radially from the center of the rod; that is, one end of such edge is in line axially with the rod, or substantially so, as illustrated most clearly in Figs. 8, 9 and 10. The cutter rod has capacity 30 for oscillatory as well as vertical movement within defined limits as above mentioned. It is supported at its lower end in a vertical bushing or bearing 71 which is screwed or otherwise secured to the forward extension 35 of a bracket 73 on the rear wall of the casing. The rod is maintained normally away from the die plate about the thickness of the fabric, occupying that position while rotating and while the feed is in operation, 40 as will hereinafter appear. In the present instance the means for thus lowering the cutter rod comprises a spring-actuated crank lever 74 having one end thereof forked to receive a suitably-disposed collar 75 on the 45 rod. The crank lever is pivotally supported on a lug on the wall of the casing and the longer arm of the lever is yieldingly connected with said wall by a retracting spring 76. The free end of this arm bears against 50 an adjustable stop in the wall of the casing, such as the set-screw 77, which stop by limiting the outward movement of the opposing lever arm permits the extent of 55 downward movement of the cutter rod and cutter to be nicely predetermined, as the thickness of the fabric may require.

The coöperative relation of the cutter and feed mechanisms is such that when the die plate is engaged with the fabric and the 60 relief is brought adjacent the centrally-disposed end of the cutter as hereinafter described, the cutter is caused to recede from the relief through an arc of about 120°, and concurrently therewith the feed motion 65 advances the work to bring the relief in

contact with the centrally disposed end of the cutter. This done the cutter swings in the opposite direction until its edge contacts longitudinally with the relief, such latter movement being comprised anywhere within an arc of about 240°; or, in other words, the cutter is movable in one direction about one-third of a rotation away from the relief and in a reverse direction about two-thirds of a rotation toward the relief. The 70 cutter is now raised to engage the fabric and press it against the die plate. In this motion the cutter does not sever the fabric, but simply holds it in place while the inner surface of the cone and the co-acting eccentric member are setting the feed in position to reengage the fabric for a succeeding feeding operation. When the feed is thus set and engaged with the fabric the cutter is raised to sever the fabric, and then lowered sufficiently to clear the fabric. The 75 cutter is then turned away from the relief through one-third of a rotation and at the same time the fabric is advanced by the feed motion. This cycle of operations is repeated until the trimming of the fabric has been completed.

By reference to Figs. 8, 9 and 10 of the drawings the successive angular positions of the cutter will be readily understood. In Fig. 8 the cutter is shown in the position which it occupies upon the completion of its cutting movement. In Fig. 9 the cutter is shown, in the position which it occupies when swung away from the relief through one-third of a rotation, the dotted lines and arrow heads indicating the extent and direction of its backward movement. It is to be noted, parenthetically, that the feed takes place during this movement. In Fig. 10 the cutter is shown in the position which it occupies when swung toward or in the direction of the relief through two-thirds of a rotation, the dotted lines and arrow heads indicating the possible extent and direction of such movement.

Inasmuch as the cutter recedes from the relief through about one-third of a rotation and returns thereto through about two-thirds of a rotation, it follows that it actually advances one-third of a rotation, and hence, under normal conditions, in three operations of the cutter a complete rotation forward can be effected. However the amount of the turning movement in the forward direction is not always two-thirds, but depends upon the contour of the relief on the fabric, which itself positively limits the forward turning movement of the cutter and determines the position of the cutter for the 115 severing operation.

To insure the initial positioning of the relief against the axial end of the cutter, provision is had whereby the cutter, preparatory to the trimming operation, severs the fabric 120

diagonally until the relief contacts with such end of the cutter. Accordingly the cutter rod is provided with a laterally-extending stud 78 into the rotary path of which a 5 suitably-disposed stop lever 79 is adapted to be set in order to limit the forward movement of the cutter rod to about one-third of a rotation. The lever is pivotally supported on a suitably-disposed bracket 80 in the casing, one arm of the lever acting as a stop for the stud, and the other arm extending to the outside of the casing. The extent of movement of the lever in one direction is determined by a stop pin 81 on the bracket and in 10 the other direction by the wall of the casing. The machine is started with the lever set in the path of the stud, and thus the cutter severs the fabric on a line diagonally of the direction of travel of the fabric until the 15 cutter contacts with the relief. Thereupon the lever is manually swung out of the path of the stud in order to permit the machine to perform its trimming operation along the boundary defined by the relief.

20 25 The means herein illustrated for effecting and controlling the vertical clamping action of the cutter rod includes a lever 82 which is pivotally mounted at one end on a suitably-disposed lug on the casing. The 30 free end of this lever is provided with a laterally extending lip 83 which lies directly below the collar 75 on the cutter rod, whereby when the lever 82 is raised the lip contacts with the collar and raises the cutter 35 rod, and when the lever is depressed said lip times the descent of the rod. This lever is connected by means of a link 84 with one arm of a bell-crank lever 85 which is pivoted on a stud on the wall of the casing, the other 40 45 arm extending laterally adjacent the cam 47 and being provided with a roll 86 which runs in the cam-groove. Hence during the rotation of the cam the crank lever 85 is oscillated and the requisite vertical motion imparted to the cutter-rod controlling lever 82.

50 55 The means herein illustrated for effecting and controlling the turning motion of the cutter rod is as follows: Mounted to rotate on the bushing 71 is a pinion 87 provided with a conical clutch socket 88 with which co-acts an internal cone member 89 slidably fitted to the bushing and to the cutter rod, one or the other of the clutch members being faced on its acting surface with leather 90 or the like. The clutch cone 89 is splined to the cutter rod so that while they shall be rotatable as a unit yet they may be movable vertically independently of each other. The clutch cone is held normally in active position by means of a suitably-disposed spring 890. In the present instance a flat spring is employed, one end thereof being secured to a bracket 891 on the inner wall of the casing and the other or free end pressing upon the 60 65 hub of the clutch cone. The bracket is

loosely fastened to the wall by an inner screw 892 below which is disposed an exteriorly projecting set screw 893, the point of which bears against the back of the bracket. By relative adjustment of the screw 893 the bracket may be tilted more or less in order to vary the force of the spring on the clutch cone, as may be desired. The pinion meshes with a horizontal rack 90 which is slidably fitted at its respective ends 75 to guides, provided for instance in the bracket 73 and in a suitably-disposed bracket 91 on the casing, whereby the reciprocation of the rack positively oscillates the pinion and its associated clutch member. In the 80 present instance the rack is pivotally connected to the lower arm of a lever 92 which is pivoted on a stud on the wall of the casing, the upper arm of such lever being connected by means of a link 93 with the upper 85 end of a lever 94 also pivoted on a stud on the wall of the casing. This lever 94 is connected by means of a link 95 with the depending arm of the crank lever 85 so as to partake of the motion of the latter, and 90 thus through the mechanism just described effect the timely reciprocation of the rack. Fast on the hub of the clutch cone 89 is a ratchet wheel 96 with the teeth of which co-acts the tooth 97 of a dog 98 which is pivotally mounted on an extension of the bracket 73. The dog is held normally in engagement with the ratchet by means of a suitably disposed spring 99, and is provided with a pin 100 which depends into the path of a cam bar 100 secured to and reciprocable with the rack. The acting face of the cam bar comprises two step surfaces 101, 102 connected by an incline 103, such surfaces being so disposed in relation to the rack that during each stroke of the 105 latter the pin 100 passes from one surface to the other, and the dog is thereby in one period moved and held out of engagement with the ratchet wheel, and in the other period is permitted to engage and remain in engagement with said wheel. When the dog is disengaged from the ratchet wheel the clutch cone is free to rotate, and hence the rotation of the pinion and its associated clutch socket by the movement of the rack is transmitted 110 to the former member and imparted to the cutter rod. When, however, the dog is engaged with the ratchet wheel, the clutch cone being locked is unaffected by the action of the pinion and its clutch-member 88.

115 The operative periods of the cutter actuating and controlling devices just described will appear from the following description of the operation of the machine:

120 The die-plate is lowered similarly to the presser foot of a sewing machine. Power is then applied to the drive wheel 49, and thereby the cam 47 is positively rotated. The fabric is then fed by hand under the die-plate until the fabric is engaged by the 130

feed. The edge of the relief on the fabric is brought into contactual relation with the axially disposed end of the cutter, preferably through a preliminary severing operation of the cutter as will hereinafter appear. The feed is given a three-phase motion, that is, the feed head being down and eccentric to the axis of the cutter rod, is moved vertically upward to engage the fabric; then horizontally to a position concentric with the cutter rod so as thereby to advance the fabric toward the cutter, and then lowered on a diagonal path to its down or set position preparatory to a succeeding en- 10 gaging and feeding operation; and the cutter is given its timely oscillation and vertical reciprocation relative to the motion of the feed.

In Fig. 1 the various parts, including the cam, are shown in the relative positions which they occupy when the feed is engaged with and before it leaves the fabric at the end of the feeding movement; that is to say, the feed is raised and forward; the frame 20 with its ring, is down; the lifting lever 82 is in its extreme down position, and the cutter rod also is in its down position with the cutter swung backward. In the succeeding rotation of the cam the sequence of operations is as follows:

In the first quarter-turn of the cam the feed remains engaged with the fabric; the frame with its ring remains down; the rack is moved rearward a full stroke, that is, to 30 the right as viewed in Fig. 1, and the lifting lever is raised to press the cutter against the fabric and thus hold the latter against the die plate. In this stroke the clutch cone is unrestrained by the dog and ratchet, and hence the cutter rod is rotated concurrently 40 with the pinion, the cutter being swung toward the relief. Unless its travel be interrupted the cutter will turn about two-thirds of a rotation; but owing to the opposing relief of the fabric the movement of the cutter is checked; that is, the leading side of the cutter contacts longitudinally with the relief and the latter consequently determines the cutting position of the cutter. In the 45 continued travel of the rack the pinion turns idly, by reason of the clutch socket slipping on the restrained clutch cone. At the end of this idle interval the cutter is pressed against the fabric by the lifting lever. At 50 this stage the cutter does not sever the fabric; it simply presses the fabric against the die-plate and holds the fabric while the feed is being returned to its set position eccentric to the axis of the cutter rod as previously mentioned.

It is to be here noted that during the first half of the rearward stroke of the rack the dog drags idly upon the ratchet teeth, and during the remainder of the stroke the cam 55 surfaces 103, 101 of the cam bar contact with

the depending pin of the dog and thus disengage the dog from the teeth of the ratchet wheel. By virtue of such action of the cam surfaces on the dog the clutch cone will be unrestrained during the first half of the suc- 70 ceeding or forward stroke of the rack in order to effect the reverse movement of the cutter rod to swing the cutter away from the relief, as will be hereinafter described in connection with the final quarter turn of the 75 cam in its rotation.

In the second quarter-turn of the cam the feed is lowered, and as the hollow cone 81 descends the action of the opposing eccentric on its inner wall deflects the feed to its initial or set position eccentric to the axis of the cutter rod preparatory to reengagement with the fabric. In this movement of the cam the frame remains in its down position; the lifting lever 82 in its raised position, and 80 the rack in its retracted position.

In the third quarter-turn of the cam the feed is raised to reengage the fabric, and the frame is elevated, the stud 68 on the latter thus impinging against the lower end of the 90 cutter rod and forcing the positioned cutter up to sever the fabric. During this period the lifting lever 82 remains in raised position and the rack retracted.

In the final quarter-turn of the cam the 95 several parts resume their first-described positions relative to each other, that is, the feed remains up and moves the fabric toward the axis of the cutter; the frame is lowered and the rack is moved forward, that 100 is, to the left as viewed in Fig. 1. In one part of this stroke owing to the disengagement of the dog from the ratchet wheel of the clutch cone, the cutter rod is turned a distance of about one-third of a rotation to 105 swing the cutter away from the relief, but in the remainder of the stroke the cutter rod and cutter are at rest on account of the locking of said cone by the engagement of the dog with the ratchet wheel. During this 110 final movement of the cam in its rotation, the eccentric of the cutter rod and the ring of the descending frame relatively co-act with the interior and exterior walls respectively of the hollow cone, the ring positively 115 acting to shift the cone to a central position and thus moving the feed in a manner to advance the fabric toward the cutter.

It is to be noted that the fabric is advanced by each forward movement of the 120 feed a distance equal to the length of the last preceding cut; that in such movement the trimmed edge of the fabric comprised by the relief, contacts with the axially disposed end of the cutter, and that, by virtue 125 of the eccentric and cone connections between the cutting and feeding devices, the feed is brought into accurate position for each succeeding feed movement, irrespec- 130 tive of the contour or outline of the relief,

During the above-described trimming operation the mutilated flange of the sleeve 60 in its rotation intermittently co-acts with the opposing surface of the bearing member 63 in a manner to brake or retard the forward movement of the cutter in opposition to the rotation of the friction clutch, and thus insure the accurate disposition of the cutter longitudinally of the relief of the fabric; that is to say, the cutter, in virtue of its position laterally of the axis of the cutter rod, tends to twist or cant said rod and thus cause the lower cut edge of the flange to bind against its seat in the member 63, when the cutter is swung forward into longitudinal contact with the relief, as previously mentioned.

Although the fabric may be preliminarily cut in any suitable manner and properly applied to the machine to bring the relief into operative contact with the axial end of the cutter, I have devised and prefer to use the means hereinbefore described for initially severing the fabric by actuation of the cutter; that is to say, the stop lever 79 is set in the rotary path of the stud 78 on the cutter rod so as to limit the stroke of the cutter toward the relief to an arc of about 120°. So long as the movement of the cutter is thus limited the cutter operates to sever the fabric in a straight line diagonally of the direction of travel of the fabric. When the fabric is cut and advanced a sufficient extent to bring the relief in contact with the axial end of the cutter, the lever 79 is manually swung out of the path of the stud on the cutter rod as previously mentioned. This done the cutter, being free to continue its movement toward the relief, swings until its edge contacts longitudinally with the latter. The machine then proceeds with the trimming operation throughout the course defined by the configuration of the relief as hereinbefore explained.

It is to be noted that for certain kinds of fabric a light slender cutter bar may be used instead of the rod and cutter herein illustrated; and also that the cutting mechanism may be constructed and arranged to sever the fabric with a downward instead of an upward stroke.

I claim—

1. In a machine of the class described, a cutter having positioning and cutting movements, the extent of the former being determined by lateral contact of the cutter with the projecting surface configuration of the material to be severed, means for imparting the positioning movement to the cutter, and means for imparting the cutting movement to the positioned cutter.
2. In a machine of the class described, a cutter having a rotary positioning movement and a longitudinal cutting movement, the extent of the former being determined

by lateral contact of the cutter with the projecting surface configuration of the material to be severed, means for imparting the positioning movement to the cutter, and means for imparting the cutting movement to the positioned cutter.

3. In a machine of the class described, a cutter movable in a path interrupted by the relief of the material to be severed, whereby lateral contact of the cutter with such relief determines the severing position of the cutter, means for moving the cutter in said path, means for effecting relative movement of the fabric and cutter in a path longitudinally of the relief, and means for actuating the cutter to sever the fabric when the cutter is positioned by its contact with the relief.

4. In a machine of the class described, a feeder, a cutter movable in a path interrupted by the relief of the material to be severed, said relief affording a guide for the edge of the cutter as the material progresses, means for moving the cutter in said path, and means for actuating said cutter itself to sever the fabric when the cutter is positioned by contact with the relief.

5. In a machine of the class described, a cutter, means for rotating the same about its longitudinal axis to position the cutter itself laterally against the edge of the relief for a severing operation, and means for thereafter longitudinally reciprocating the cutter to effect the severing operation.

6. In a machine of the class described, a cutter rod having at one end thereof a radial cutting edge, means for rotating said rod about its longitudinal axis to position the cutter for a severing operation, and means for thereafter longitudinally reciprocating said rod to effect the severing operation.

7. In a machine of the class described, a cutter rod having at one end thereof a radial cutting edge, means for oscillating said rod about its longitudinal axis whereby in alternate strokes it is positioned for the severing operation, and means for longitudinally reciprocating said rod to effect the severing operation when it is thus positioned.

8. In a machine of the class described, feed mechanism, an oscillatory cutter adjacent thereto, one end of which cutter coincides with its axis of oscillation and is adapted to be positioned by the relief of the fabric to be severed, means for oscillating the cutter at predetermined intervals during the progress of the fabric, and means for periodically reciprocating said cutter longitudinally of its axis.

9. In a machine of the class described, feed mechanism, an oscillatory cutter adjacent thereto, one end of which cutter coincides with its axis of oscillation, means for oscillating the cutter at predetermined inter-

vals during the progress of the fabric, whereby the relief of such fabric determines the severing position of the cutter, means for moving the positioned cutter in the direction of its length into contact with the body of the fabric, and means for thereafter forcing the cutter through the fabric.

10. In a machine of the class described, a cutting element mounted for rotary and longitudinal movement, means for actuating the said element to impart an oscillatory movement thereto and also longitudinal reciprocatory movement at predetermined intervals, a feed element mounted for variable movement, and means for actuating said feed element whereby the fabric is intermittently advanced in close relation to the cutting element.

11. In a machine of the class described, a cutting element mounted for rotary and longitudinal movement, means for actuating the said element, a feed element mounted for variable movement, means for actuating said feed element whereby the fabric is intermittently advanced in close relation to the cutting element, and means whereby the said feed element is positively set for a succeeding operation at the end of each return movement.

12. In a machine of the class described, a feed element having capacity for variable movement, means for actuating said element, a cutting element having a part thereof in close relation to the path of the fabric, means whereby the said cutting element is oscillated in respect to the edge of the fabric, means whereby the feed in its return movement is positioned for a succeeding feeding operation, and means whereby the cutting element is reciprocated longitudinally of its axis at predetermined intervals.

13. In a machine of the class described, cutting mechanism, feed mechanism including a feed element adapted to engage and feed the fabric, said feed element mounted for variable movement, and means under the control of the cutting mechanism adapted to co-act with the feed mechanism to set the feed element preparatory to each feeding operation thereby.

14. In a machine of the class described, feed mechanism, cutter mechanism including a rotary cutting element, means for oscillating the said element whereby the said element in alternate strokes is positioned by the relief, means associated with the cutter mechanism arranged to co-act with the feed mechanism for setting the latter to feed the fabric in the direction of the cutting element after the latter is thus positioned, and means for reciprocating the positioned element.

15. In a machine of the class described, cutting mechanism including a rotary cut-

ting element, and means for oscillating said element including a friction clutch connection and intermittent locking means therefor, whereby the said cutting element in alternate strokes is positioned by the relief of the fabric.

16. In a machine of the class described, a cutter rod and cutter, means for periodically reciprocating said rod longitudinally of its axis, a pinion, a friction clutch connection between said pinion and the cutter rod, a rack for oscillating the pinion, intermittently-acting locking devices for the clutch connection, means controlled by the rack for periodically effecting the unlocking of the clutch connection, and means for periodically reciprocating the rack.

17. In a machine of the class described, cutter mechanism including a rotary cutting element, means for oscillating the said element, whereby the same in alternate strokes is positioned by the relief, a brake device for the cutter mechanism, and means for reciprocating the positioned cutting element.

18. In a machine of the class described, a cutter rod and cutter, means for oscillating the said rod whereby the said element in alternate strokes is positioned by the relief, a rotatable brake member with which said rod is slidably connected, a stationary brake seat therefor, and means for periodically reciprocating the said rod longitudinally of its axis.

19. In a machine of the class described, feed mechanism, including a hollow cone member and means for imparting variable movement thereto, a ring encircling said member, means for periodically raising and lowering the ring, a cutter rod extending axially through said cone member and provided at one end with a cutter, means for oscillating said rod whereby the cutter in alternate strokes is positioned by the relief, a brake member with which said rod is slidably connected, a stationary brake seat therefor, an eccentric on said brake member arranged to co-act with the inner wall of the cone member, and means for periodically reciprocating the said rod longitudinally of its axis.

20. In a machine of the class described, feed mechanism, a die member, a cutting element, and means whereby said cutting element is actuated to clamp the fabric against the die member during the return stroke of the feed mechanism and then to sever the fabric.

21. In a machine of the class described, feed mechanism, a die member, a cutter element, means for moving said element laterally toward and from the line of severance of the fabric at predetermined intervals, and means for longitudinally actuating said ele-

- ment whereby it is set to clamp the fabric against the die member during the return stroke of the feed member and then to sever the fabric.
- 5 22. In a machine of the class described, feed mechanism, a die member, a cutter rod and cutter, means for periodically oscillating said rod and cutter, means for maintaining the said rod and cutter yieldingly depressed, means for raising the rod at one period to press the fabric against the die member, and means for further raising the rod at another period to sever the fabric.
- 10 23. In a machine of the class described, the combination of feed mechanism, cutting mechanism, including a rotary cutting element, means for oscillating the said element whereby the said element in alternate strokes is swung laterally toward the relief, and manually operative means for temporarily limiting the extent of such alternate stroke.
- 15 24. In a machine of the class described, the combination of feed mechanism, cutting mechanism including a rotary cutting element, and means for oscillating the said element including a friction clutch connection and intermittent locking means therefor, whereby the said cutting element in alternate strokes is swung laterally toward the relief of the fabric, together with means for temporarily reducing the extent of the movement of said cutting element toward the fabric.
- 20 25. In a machine of the class described, a cutter rod and cutter, means for periodically reciprocating said rod and cutter longitudinally of its axis, a pinion, a friction clutch connection between said pinion and the cutter rod, a rack for oscillating the pinion, intermittently-acting locking devices for the clutch connection, means controlled by the rack for periodically effecting the unlocking of the clutch connection, means for periodically reciprocating the rack, a stop on the cutter rod, and manually operative means movable into and from the rotary path of said stop.
- 25 26. In a machine of the class described, feed mechanism including a feed element having capacity for variable movement, cutting mechanism including a cutter element, having capacity for horizontal oscillation and vertical reciprocation, a system of lever and link connections for controlling the periodic positions of the feed and cutter ele-
- ments, and a cam for actuating and controlling said devices.
- 30 27. In a machine of the class described, a feed element, a cone supporting the same, actuating mechanism for the cone including a universal joint connection, a reciprocating frame having a ring encircling the cone, means for reciprocating said frame, a cutter rod and cutter mounted for horizontal oscillation and vertical reciprocation, a setting device located within the cone, said device being eccentric to and rotatable by the said rod yet permitting vertical movement of the rod, means for periodically oscillating said rod and cutter, means for normally depressing said rod and cutter, means for partially raising said rod and cutter, and means on the frame for subsequently bearing against and further raising the cutter rod.
- 35 28. In a machine of the class described, cutting mechanism including a rotary cutting element, frictional means for rotating said element from and to the cutting position, and means for actuating said frictional means.
- 40 29. In feed mechanism, a feed element, and means for imparting variable movement thereto, whereby the said element is engaged with the fabric, moved to advance the fabric, and then moved to a set position, said means including a member controlled by the fabric.
- 45 30. In feed mechanism, a feed element, means for imparting an up and down motion to said element, means for shifting said element forward when it is in up position, and means for shifting said element rearward to set position during its downward movement, said last-named means including a member controlled by the fabric.
- 50 31. In feed mechanism, a feed element, a cone supporting the same, actuating means for the cone including a universal joint connection, a reciprocating frame having a ring encircling the cone, means for reciprocating said frame, a setting device located within the cone, and means controlled by the fabric for determining the position of said device relative to the cone.
- 55 32. Signed at New York in the county and State of New York this 29th day of December A. D. 1913.
- CHARLES D. MATTISON.
- Witnesses:
- JOHN R. NOLAN,
B. CHANDLER SNEAD.
